CLAIM

The ornamental design for a combined pin and guide for positioning an artificial tooth, as shown and described.

DESCRIPTION

FIG. 1 is a front elevational view of a combined pin and guide for positioning an artificial tooth showing my new design;

FIG. 2 is a left side elevational view thereof, the right side being a mirror image;

FIG. 3 is a rear elevational view thereof;

FIG. 4 is a top plan view thereof;

FIG. 5 is a bottom plan view thereof;

FIG. 6 is a top perspective view thereof; and,

FIG. 7 is a bottom perspective view thereof.
